UNITED STATES PATENT OFFICE.

DANIEL LOWELL LAMSON, OF FRYEBURG, MAINE.

HEATER.

SPECIFICATION forming part of Letters Patent No. 248,480, dated October 18, 1881.

Application filed May 4, 1881. (No model.)

To all whom it may concern:

Be it known that I, D. LOWELL LAMSON, of Fryeburg, in the county of Oxford and State of Maine, have invented certain useful Improvements in Heaters, of which the following is a specification.

The object of this invention is to construct a heater for burning coal or wood, or both together, whereby advantage may be taken of the cost or convenience of the fuel-supply, and the fire be better adapted to the condition of the weather.

Figure 1 is a sectional side elevation of the furnace inclosed in a suitable air-chamber on line *y y*, Fig. 2. Fig. 2 is a vertical sectional elevation on line *x x*, Fig. 1.

Similar letters of reference indicate corresponding parts.

In the drawings, A represents the coal-burning fire-pot chamber, preferably in the form of the inverted segment of a cone, provided with grate A', having shaking-bar *a*, and with ash-pit A², access to which is had through the front plate, B, of the furnace by the doors *b c d*, respectively.

With its front end resting in the front plate, B, and its rear supported in a shoe, *f*, on the top of the coal-burning chamber A, or in any other convenient and suitable manner, is the horizontal wood-burning fire-pot or cylindrical chamber C, which is preferably of oval or ellipsoidal cross-section, as shown, and designed to be of sufficient length to admit wood of suitable length. Said cylinder C is elevated far enough above the cylinder A to permit effective radiation of heat from the bottom of the former and the top of the latter, a radiating-space, O, being formed between them.

The main smoke-flues D E are arranged in the form of a cross, centrally intersecting each other above the chamber or cylinder C, and from the top of the coal-burning chamber or cylinder A flues *g g* extend upon either side of the chamber or cylinder C into the transverse flue D, while shorter flues *h h*, at either end of the chamber C, connect with the longitudinal flue E.

The whole device may be inclosed in a suitable brick chamber, F, as shown in Fig. 1, from whence it is designed to convey the hot air to the different rooms of the house.

In the cylinder or chamber C, by the more rapid consumption of wood and the large radiating-surface, a quick and intense heat may at any time be obtained, while the ignition and burning of coal being slower, a longer continued heat can be maintained in the cylinder or chamber A, while both together in their full capacity will supply as much heated air as two ordinary furnaces of similar dimensions set 55 separately, and at a cost of construction but little exceeding that of a single heater. Thus the capacity and power of two furnaces is practically attained at about the expense of one.

By the adjustment of suitable flue-dampers, 65 *n n*, that are designed to be within easy reach of the operator, the combustion in either chamber or cylinder A C may be regulated without interfering with the other, and the flues of one chamber or cylinder closed when the other cylinder is in use separately.

In a furnace of this construction there is a great amount of radiating-surface within the inclosing air-chamber.

The smoke-flues D E are designed to be provided with dampers, as aforesaid, to direct the draft in whatever direction may be best for good combustion of the fuel, and the damper *m* in the front flue, *h*, should be ordinarily closed, but may be opened for a more direct 70 course for the smoke whenever the wood-furnace door is opened, or when too much heat is being radiated and it is desirable to reduce the fire.

Having thus fully described my invention, I 85 claim as new and desire to secure by Letters Patent—

1. In a heater, the combination of the coal-burning chamber A and wood-burning chamber C, connected by flues D E *g h*, substantially 90 as herein shown and described.
2. In a heater consisting of a wood-burning chamber and a coal-burning chamber arranged one above the other, the radiating-space O between them to permit free radiation from the 95 bottom of the one and the top of the other, as set forth.

DANIEL LOWELL LAMSON.
